INTERNAL-COMBUSTION ENGINE

Frank J. Fette, Tampa, Fla.; Joseph F. Fette ex-
ecutor of said Frank J. Fette, deceased

Application June 6, 1946, Serial No. 674,880

3 Claims. (Cl. 123—44)

1

This invention relates to internal combustion engines of the two-cycle, "Diesel" type and particularly of that character in which the force of a piston is exerted upon an endless cam track to convert reciprocation of the piston into rotary movement of a shaft.

A primary object of the invention is the provision of a light motor, of simple and rigid construction, capable of high speed and one in which the forces are counterbalanced to minimize vibration.

In the drawings illustrating a preferred embodiment of the invention, Figure 1 is a side elevation of the engine; Fig. 2 is a vertical central section with parts in elevation; Fig. 3 is a diagrammatic view to show the position of the cams at corresponding positions of the pistons; Fig. 4 is a front elevation of the engine with part of the casing and of the central webs broken away and Fig. 5 is a central horizontal section in the plane indicated by the line V—V of Fig. 4.

Upon base members 1 and 2, are secured upright webs 3 and 4 respectively. A front casing member 5 is shown at the left in Fig. 4 and at the top of Fig. 2 as having a flange 6, with a corresponding bottom flange 7, and in Fig. 5 a left side flange 8, all secured to the web member 3 as by bolts 9. The same casing member 5 has a top flange 10, a bottom flange 11, and a side flange 12 secured to the web member 4 by bolts 13. The space between the webs 3 and 4 is indicated at 14 at the top and bottom of Fig. 4.

The rear casing member 15 has flanges 16 and 17 seen in Fig. 2 and flange 18 seen in Fig. 5 corresponding to the flanges 6, 7, and 8 respectively, of the front casing member and held to the web 3 by the same bolts 9. The member 15 has a central hub 19. It also has flanges 20 and 21 seen in Fig. 1 and flange 22 seen in Fig. 1, corresponding to the flanges 16, 17, and 18 respectively of the front casing member 5 and secured to the web 4 by the same bolts 13.

The central confronting edges of the webs 3 and 4 are cut out on circular arcs to receive a cylindrical water jacket 23 which may advantageously be fabricated from steel tubing pierced on opposite sides for a transverse tubular member 24 forming a piston chamber. The top of the member 24 is preferably welded to the jacket 23, but the bottom will have a packing gland of which the outer member 25 will be welded to the jacket and the inner member 26 will have a threaded engagement in the member 25 to permit sliding when the tube 24 expands as the engine is run.

The rear end of the jacket 23 is closed by a

2

plate 27 having a central, outwardly-opening socket 28 for a bearing for the end of the shaft 29. The central hub portion 19 of the casing member 15 contains a roller bearing for the shaft 29.

Mounted for reciprocation within the chamber 24 are two pistons 30 each having a stem 31 projecting from the end of the chamber into a space 14 between the webs 3 and 4 and each stem having lateral pairs of flanges 32 engaging opposite faces of a web 3 or 4 whereby the outer ends of the stems 31 are guided by the webs to move in a straight line with a minimum of side thrust on the walls of the cylinder, and to prevent a tendency to rotate because of opposing pressures of the two cams engaged by the rollers mounted on the stems.

Keyed to the shaft 29 is a dished carrier member 33 to the face of which is secured a disk 34 having on the surface remote from the carrier member, a substantially elliptical cam 35. A roller bearing 36 is shown as interposed between the cam disk and the outer surface of the jacket 23.

25 A corresponding disk member 37 having the inwardly extending cam 38 of the same shape and size as cam 35, is mounted for rotation on the outer surface of the other end of the cylinder 23.

The cam disk 34 has secured thereto a ring gear 39 and cam disk 37 has a similar gear 40. Between these two confronting gears on the cam disks, are interposed four smaller bevel gears 41, 42, 43, and 44, of which the idler gear 41 is seen at the left in Figs. 4 and 5 and a fan-drive gear is seen at the right in the same figures. A second idler gear 43 is indicated by broken lines at the upper right in Fig. 4 and a second fan-drive gear 44 is indicated in broken lines at the upper left.

40 As best seen in Fig. 2, the stems 31 of the pistons 30 are each provided on opposite sides with rollers 45 engaging the inner surface of a cam 35 or 38 and with rollers 46, engaging the outer surface of one of the cams. In Fig. 4, the cam 38 is shown in section, being on the same side of the webs 3 and 4 as the observer, the plane of section being that indicated by the broken line IV—IV of Fig. 2, between the right-hand surface of the cam disk 37 and the adjacent ends of the rollers 45 and 46.

In the cam position of Fig. 4, the major axes of both cams are vertical and the engagement of the rollers 45 with the inside of the cams prevents any further outward movement of the pistons 30 away from each other in the cylinder 24.

In the broken line position of the cams in Fig. 4 with their major axes horizontal, the pistons are at their inner limits of their strokes and the engagement of rollers 46 with the outer surfaces of the cams would prevent further inward movement even if the air between the ends of the two pistons were not compressed, as of course it always is in normal operation. Usually, the rollers 46 may be entirely out of contact with the cam as will appear later.

A flywheel 47 on the shaft 29 may be used to start the rotation of the shaft and of the member 33 keyed thereon, thus causing rotation of the cam disk 34 and of the gear 39 attached thereto. The gears 41, 42, 43, and 44 in mesh with the gear 39 will start the gear 40 to rotating in the opposite direction to that of gear 39, carrying with it the cam disk 37 and the cam 38. The two cams moving in opposite directions will push inward on the rollers 45 and cause the two pistons to move toward each other, compressing the air in the chamber between them until they reach the innermost limit of the compression stroke with a certain clearance between them.

At this central point of the chamber 24, always unobstructed by the pistons, an injection nozzle 48 is secured within the chamber wall, supplied by a tube 49 leading from a pump 50 actuated by a rotary cam 51 controlled by a governor 52, which may be of the form fully disclosed in my Patent No. 2,149,591, issued March 7, 1939.

The pump and cam are set to cause the injection of liquid fuel into the chamber at the moment of greatest compression of air between the two pistons, the heat of compression being sufficient to ignite the fuel. The momentum of the flywheel carries the cams past the dead centers at the end of the compression stroke at which time the major axes are horizontal and the cams immediately begin to recede from the pistons. If no injection of fuel has occurred and no combustion, the cams will act upon the rollers 46 to draw the pistons outward until they reach the outer limit of movement, ready for the next inward movement of compression. If fuel has ignited, the force of expansion of the hot gases thrusts the rollers 45 against the inclined walls of the cams to cause their rotation and the continued rotation of the shaft and flywheel. The thrust will be equal against both cams.

Figure 3 is a diagram intended to show the relative positions of the cams and pistons at different degrees of rotation of the flywheel. To avoid unnecessary complexity, the vertical full-line position of the cam 38 shown in Fig. 4 and the broken-line horizontal position have both been omitted from Fig. 3.

The narrowest pair of rectangles formed by long dashes at *a*, *a*, in Fig. 3, indicate the innermost position of the pistons at their closest approach to each other, with cams then in the dash-line position of Fig. 4. These rectangles have their tops connected by long-dash stems 31a with the circles 45a representing the rollers 45. The next rectangles at *b*, *b*, indicated by dashes separated by two dots and connected by similar lines 31b to circles 45b show the small outward movement of the pistons while the cam disks each rotate through ten degrees from the horizontal to the dash-double-dot positions 35b and 38b. The dash-dot rectangles at *c*, *c*, connected by stems 31c with rollers 45c represent a total outward movement of the pistons through forty-five degrees of rotation of the cams from the horizon-

tal to the positions at 35c and 38c. This is not yet half of the longitudinal piston stroke which will continue outward during the next forty-five degrees of rotation of the cams to the short-dash positions of the pistons at *d*, *d*. This is of course, the vertical position of the cams in Fig. 4.

The wall of the chamber 24 has formed there-in a plurality of elongated perforations 53 serving as exhaust ports for the gases of combustion. 10 A member 54 surrounding the cylinder 24 and welded thereto, provides a passage to receive the exhaust from the ports 53, the outer end of the member 54 being shown as having a flange 55 for attachment to the casing member 5. One end of an outer exhaust channel member 56 is secured as by a flange 57 to the casing 5 in line with the member 54 and the other end is secured to a fan casing 58 as by a flange 59. Within the casing 58, a fan 60 is driven by the shaft of the gear 42.

The cylinder 24 has a second set of ports at 61 surrounded by a member 62 having a passage therein for scavenging air. The outer end of the member 62 has a flange 63 for attachment to the 25 casing member 5 in alignment with the outer member 64 leading to the casing 65, within which is a fan (not shown), the arrangement being substantially identical with the exhaust passage 56 and fan 60 just described, and the fan being driven by the gear 44.

The lower piston 30 begins to uncover the ports in Fig. 2 at about sixty degrees of rotation of the cams from the innermost position *a* of Fig. 3 and the escape of the gases is facilitated by the suction set up by the fan as soon as the ports open. At about seventy-five degrees of rotation, the scavenging air ports 61 begin to be uncovered and remain open for about thirty degrees of rotation of the cams, during which period, the fan 40 in the casing 65 acts as a blower to drive air after the escaping combustion gases for complete scavenging of the cylinder.

The water jacket 23 has baffles 66 welded longitudinally of the walls on opposite sides above and below the central portion of the cylinder 24. Cooling water is delivered by pipes 67, 68, and 69 to the space between the baffles and flows into the upper and lower cavities around the cylinder to escape through the pipes 70 and 71.

50 The casing formed between the members 5 and 15 may hold a sufficient quantity of oil in its lower portion for proper and efficient lubrication of the cams, the gears, and the bearings of all the rotating members and of the piston rings. 55 An inlet for oil is closed by the plug 72 at the top of the casing and a drain plug 73 is seen at the bottom in Fig. 4. Ready access to the nozzle 48 is provided by a tube 74 of a size to admit a socket wrench.

60 The many advantages of the structure herein illustrated and described will be evident to those skilled in the art. Many parts can be made of tubing and of sheet metal by simple welding methods while other parts can be made as light alloy castings.

The pistons are guided in straight line movement without side thrusts upon the cylinder walls and the pressure exerted by and upon the cams is equal on both sides of the piston. Two power strokes occur in each revolution of the flywheel, making high speed possible with well balanced forces because of the opposite motion of piston against piston and of the oppositely rotating disks.

I claim:

1. An internal combustion engine comprising separable casing members, a cylindrical water jacket mounted transversely of the casing and having means for circulating water therethrough, a power cylinder secured within the water jacket and set transversely thereof, cam members journaled for rotation upon the exterior of the jacket on opposite sides of the power cylinder, gears on each cam member, intermediate gears mounted for rotation on the casing and engaging the gears on the cam members to cause them to rotate in opposite directions, a cam upon each of the cam members on the sides adjacent to the power cylinder, two pistons reciprocating oppositely within the power cylinder, each piston having means bearing upon the internal surfaces of both cams to cause them to rotate upon outward movement of the pistons, means to force fuel into the space between the pistons, intake and outlet ports formed within the walls of the power cylinder and uncovered by the pistons near the ends of their outward strokes, and fans driven by the gears to cause scavenging flow of air through the cylinder when the ports are open.

2. A power cylinder having two pistons reciprocating oppositely therein, the cylinder having inlet and exhaust ports uncovered by the pistons near their points of greatest distance from each other, means for forcing fuel into the power cylinder between the pistons near their points of closest approach to each other, a cylindrical water jacket secured upon and surrounding the power cylinder over the portion between the intake and exhaust ports, the axis of the water jacket being at substantially right angles to that of the power cylinder, the outer surface of the water jacket being formed at each end as a bearing, oppositely facing cam members being mounted for rotation upon the jacket bearings and having a cam symmetrical with respect to the axis of rotation formed on each of the two confronting faces of the cam members, each piston having cam-engaging means thereon in contact with both cams, gears upon the cam members, intermediate gears engaged therewith to cause the cams to rotate

in opposite directions, and means actuated by the intermediate gears to cause movement of air through the power cylinder while the ports are open to cause scavenging of the products of combustion.

- 5 3. An internal combustion engine having a fixed power cylinder provided with intake and exhaust ports, two pistons reciprocating oppositely within said cylinder and adapted to uncover said ports near their points of greatest distance from each other, means for introducing fuel into the power cylinder between the pistons, a cylindrical supporting member formed as a hollow chamber surrounding the central portion of 10 the casing and having its exterior surface provided at each side of the power cylinder with a bearing, a cam member on each of said bearings mounted for rotation on an axis at right angles to the axis of the cylinder, a cam on each of said 15 cam members, means on each of said pistons engaging both of the cams to cause them to rotate in opposite directions, a gear on each of the confronting faces of the cam members, intermediate gears mounted for rotation on axes at right angles to the axis of rotation of the cam members 20 and engaged on their opposite sides by the gears on the cam members, and means driven by the intermediate gears to cause movement of air through the cylinder while the ports are open 25 to scavenge the products of combustion from the cylinder.
